UNITED STATES PATENT OFFICE

105,890

DESIGN FOR A BOOT

Adolph Martin Mondl, Oshkosh, Wis.

Application January 29, 1937, Serial No. 67,335

Term of patent 3½ years

To all whom it may concern:

Be it known that I, Adolph Martin Mondl, a citizen of the United States and resident of Oshkosh, in the county of Winnebago and State of Wisconsin, have invented a new, original, and ornamental Design for Boots, of which the following is a specification, reference being had to the accompanying drawing, forming part thereof. While my new design is shown as applied to boots it is also intended for other similar footwear such as overshoes, galoshes, or the like.

As shown in the drawing,

Fig. 1 is a rear perspective view of a boot showing my new design; and

Fig. 2 is a front perspective view of the same.

I claim:

The ornamental design for a boot as shown and described.

ADOLPH MARTIN MONDL.
